UNITED STATES PATENT OFFICE

2,628,791

SHUTTLE CAR AND ELECTRIC CABLE REEL

Arthur L. Lee, Upper Arlington, Ohio, assignor to
The Jeffrey Manufacturing Company, a corporation of Ohio

Original application December 3, 1947, Serial No.
789,384, now Patent No. 2,599,061, dated June
3, 1952. Divided and this application July 14,
1949, Serial No. 104,780

3 Claims. (Cl. 242—90)

1

This invention relates to a shuttle car and particularly to an electric cable reel in association with the discharge boom of a shuttle car.

An object of the invention therefore is to provide improved mechanism of the above mentioned type.

A further object of the invention is to provide an improved drive for an electric cable reel.

Other objects of the invention will appear hereinafter, the novel features and combinations being set forth in the appended claims.

In the accompanying drawings,

Fig. 1 is an elevational view of the discharge end of a shuttle car incorporating the features of my invention; and

Fig. 2 is a sectional view showing the details of the drive for the electric cable reel.

This application is a division of my application, Serial No. 789,384, filed December 3, 1947, entitled Shuttle Car, now Patent No. 2,599,061, dated June 3, 1952.

Fig. 1 of the drawings shows the discharge end of a shuttle car including a main frame or body 10 having supporting wheels, one of which is seen at 11, and a discharge boom 12. The complete shuttle car is disclosed in my Patent No. 2,599,061 above identified.

Adjacent the discharge end of the shuttle car and generally to one side of the center line of the main frame or body 10 and below at least a portion of the discharge boom 12 there is an electric cable reel 13 of relatively large diameter which is mounted for rotation on a generally upright axis. The cable reel 13 is relatively thin, measured along its axis of rotation, so that it may be positioned below the discharge boom 12 and within the confines of the main frame or body 10 without unduly restricting the clearance of the main frame or body 10.

The cable reel 13 is adapted to receive an electrical cable 14. An electric or hydraulic motor 15 drives said cable reel 13 through gearing which includes a generally upright shaft 16 having a sprocket 17 that rotates upon an axis that is parallel with the axis of rotation of the cable reel 13. Sprocket 17 meshes with an endless roller chain 18 anchored to a circular shrouding guide 19 which is rigidly attached to the top plate of the cable reel 13, as clearly illustrated in Fig. 2 of the drawings.

From Fig. 2 of the drawings it will be seen that the chain 18 is secured directly to a top plate or side member 21 of the cable reel 13 by the shroud 19. Shroud 19 includes two rings 22 and 23 that are spaced apart axially by spacer mem-

2

ber 24. The rings 22 and 23 and spacer member 24 are secured directly to the top plate or side member 21 of the cable reel 13 by a plurality of bolts, one of which is seen at 25. The rings 22 and 23 are each grooved in their facing or adjacent sides as seen at 26 and these grooves hold the chain in a circle having the same axis of rotation as the cable reel 13. It will be seen that when the chain 18 and shroud 19 are assembled and bolted to top plate 21 of cable reel 13 that the shroud causes the chain to form an internally toothed gear with which the sprocket 17 meshes to rotate the cable reel 13. The chain 18 is secured against rotation in the shroud 19 by one or more pins 27 that are anchored to the chain 18 and extend into openings in the top ring 23.

As clearly illustrated in Figs. 1 and 2 of the drawings, the electric cable reel 13 is mounted for rotation on a generally vertical or upright but inclined axis and a substantial portion thereof extends below the boom 12 and the conveyor of the shuttle car (not shown). This makes possible the employment of a relatively large reel which can handle a great length of electric cable 14 which is reeled thereon, while permitting a relatively wide conveyor or body 10 in the interest of high capacity and a body that has ample ground clearance adjacent the cable reel. This construction of the cable reel also does not interfere with the low overall height of the shuttle car which is an important characteristic of a shuttle car which may be used in low seam coal. The cable 14 is adapted to extend rearwardly from the vehicle, as illustrated in Fig. 1 of the drawings, or it may extend forwardly by being reeved around a guide sheave or roller 20.

Obviously those skilled in the art may make various changes in the details and arrangement of parts without departing from the spirit and scope of the invention as defined by the claims hereto appended, and applicant therefore wishes not to be restricted to the precise construction herein disclosed.

Having thus described and shown an embodiment of the invention, what it is desired to be secured by Letters Patent of the United States is:

1. A shuttle car including a frame, traction means supporting one end of said frame, a generally horizontal discharge boom extending at said one end and adjacent the top of said frame, a cable reel of relatively large diameter and small axial dimension located within the confines of said frame and below said discharge boom, means mounting said cable reel for rotation on a generally upwardly inclined axis, driving means for

said cable reel including a motor and a drive sprocket, means mounting said drive sprocket for rotation on an axis extending substantially parallel to the axis of rotation of said cable reel, a chain with which said drive sprocket meshes, shroud means attaching said chain to the top of said cable reel including two substantially identical axially spaced rings grooved to receive said chain and hold it in a circle having the axis of rotation of said cable reel as a center, and means securing said shroud means and said chain to said cable reel.

2. A shuttle car including a frame, traction means supporting one end of said frame, a generally horizontal discharge boom extending at said one end and adjacent the top of said frame, a cable reel of relatively large diameter and small axial dimension located within the confines of said frame and below said discharge boom, means mounting said cable reel for rotation on a generally upwardly inclined axis, driving means for said cable reel including a motor and a drive sprocket, means mounting said drive sprocket for rotation on an axis extending substantially parallel to the axis of rotation of said cable reel, a chain with which said drive sprocket meshes, and shroud means attaching said chain to said cable reel including a ring holding it in a circle having the axis of rotation of said cable reel as a center.

3. A shuttle car including a frame, a generally horizontal discharge boom extending at one end

and adjacent the top of said frame, a cable reel of relatively large diameter and small axial dimension located within the confines of said frame and below said discharge boom, means mounting said cable reel for rotation on a generally upright axis, driving means for said cable reel including a motor and a drive sprocket, means mounting said drive sprocket for rotation on an axis extending substantially parallel to the axis of rotation of said cable reel, a chain with which said drive sprocket meshes, and means attaching said chain to said cable reel holding it in a circle having the axis of rotation of said cable reel as a center.
